SAFETY VALVE FOR VISCOUS FLUIDS

Victor W. Farris, Tenafly, N. J.

Application March 16, 1948, Serial No. 15,149

1 Claim. (Cl. 137—53)

1

This invention relates to safety valves, and more particularly, to safety valves for controlling the flow of viscous fluids.

Devices of this general character have heretofore required the association therewith of external heating means for preventing the viscous fluid from freezing the valve disc, or interfering with the rapid response of said disc in accordance with the fluctuations in the fluid pressure.

Heating means so located have certain disadvantages. For one thing, they interfere with free access to the valve for adjustment or other purposes. For another, the amount of heat required to maintain suitable fluid density within the valve is excessive.

It is, therefore, the main object of the present invention to provide a safety valve for the purpose indicated which overcomes the above mentioned disadvantages by incorporating in the interior thereof heating means which does not interfere with the normal adjustment or operation of the valve and which requires the application thereto of considerably less heat than has heretofore been the case.

In the accompanying specification there shall be described and in the annexed drawing shown an illustrative embodiment of the safety valves of the present invention. It is, however, to be clearly understood that the present invention is not to be limited to the exact details herein shown and described for purposes of illustration only, inasmuch as changes may be made therein without the exercise of invention and within the true spirit and scope of the claim hereto appended.

In said drawing, the single figure is a vertical sectional view taken substantially through the center of a safety valve made in accordance with the present invention.

Referring now more in detail to the aforesaid illustrative embodiment of the present invention, with particular reference to the drawing illustrating the same, the numeral 10 generally designates a safety valve including a valve body 11 having a central chamber 12 and inlet and outlet ports 13 and 14 communicating with said central chamber, a bonnet 15 mounted on said body and providing a spring chamber 16, and a cap 17 secured at the upper end of said bonnet.

Threadedly engaged in the inlet port 13, and extending into the central chamber 12, is a high velocity nozzle 18 at the inner end of which there is formed a valve seat (not shown).

Secured intermediate the body 11 and the bonnet 15 is a baffle 19, said baffle isolating the central chamber 12 from the spring chamber 16, and

2

depending from the central portion of said baffle is a cylinder 20.

Slidably mounted in the cylinder 20 is a sleeve 21 formed on a disc-holding member 22, said disc-holding member being constructed as shown in my copending application entitled "Safety valves," Serial No. 788,901, filed November 29, 1947, and incorporating a valve disc (not shown) cooperable with the seat formed on the nozzle 18, and being secured to a valve stem 23, also as shown in said copending application.

The stem 23 rises through the spring chamber 16 and has its upper end guided in a spring-adjusting screw 24 engaged in the bonnet 15, said screw bearing against a button 25 which is loosely mounted on said stem and which, in turn, bears against the upper end of a coil spring 26 the lower end of which abuts another button 27 which is fastened on the stem 23. The screw 24 is adapted to be locked in position by a nut 28.

A plate 29 is threadedly engaged on the nozzle 18 adjacent the inner end thereof, and supported on said plate in close proximity to the disc-holding member 22, the bearing cylinder 20, and the valve disc and valve seat, as by being wrapped about said members, is a steam coil 30, said steam coil serving to heat the central chamber 12 and the elements housed therein, whereby the valve of the present invention is made capable of handling viscous fluids which would, in the absence of heat, cause the valve to stick or respond to variations in pressure in a sluggish manner.

One end of the coil 30 communicates, through a coupling 31, with any suitable source 32 of steam or other heating medium. The other end of said coil 30 communicates, through a coupling 33, with a steam outlet pipe 34.

The pipe 34 includes a T-connection 35 which communicates through a pipe 36 with a conventional trap 37 for removing from the heating system any water condensing therein.

This completes the description of the aforesaid illustrative embodiment of the safety valves of the present invention. It will be noted from all of the foregoing that the present invention provides, in a simple, efficient and inexpensive manner, a safety valve capable of controlling the flow of fluids of appreciable density. Other objects and advantages of the present invention will readily occur to those skilled in the art to which the same relates.

What is claimed is:

A safety valve comprising: a valve body provided with a central chamber, and inlet and outlet ports communicating with said central chamber;

a nozzle communicating with a source of viscous fluid the flow of which is intended to be controlled by said valve; said nozzle extending into said central chamber through said inlet port and being provided with a valve seat at the inner end thereof; a spring pressed valve disc slidably mounted in said body and cooperable with said seat; a plate mounted on said nozzle adjacent said seat and a conduit supported on said plate; said conduit communicating at one end with a source of steam independent of and exteriorly located with respect to said valve, and said conduit communicating at the other end with the atmosphere, said conduit being coiled within said central chamber about and immediately adjacent 15 said disc and seat.
